I. E. HINDMAN,
BRAKE MECHANISM FOR LIFTING JACKS.
APPLICATION FILED MAR. 2, 1917.

1,234,334.

Patented July 24, 1917.

UNITED STATES PATENT OFFICE.

ISAIAH E. HINDMAN, OF CRAFTON, PENNSYLVANIA, ASSIGNOR TO THE DUFF MANUFACTURING COMPANY, OF PITTSBURGH, PENNSYLVANIA, A CORPORATION OF PENNSYLVANIA.

Brake Mechanism for Lifting-Jacks.

1,234,334.

Specification of Letters Patent. Patented July 24, 1917.

Application filed March 2, 1917. Serial No. 152,071.

To all whom it may concern:

Be it known that I, ISAIAH E. HINDMAN, a citizen of the United States, residing at Crafton, in the county of Allegheny and State of Pennsylvania, have invented a new and useful Improvement in Brake Mechanism for Lifting-Jacks, of which the following is a full, clear, and exact description, reference being had to the accompanying drawings, forming part of this specification, in which—

Figure 1 is a sectional view, partly broken away, of a lifting jack embodying my invention.

Fig. 2 is a detail view, partly in end elevation and partly in vertical section showing the manually controlled brake device.

My invention has relation to brake mechanism for load raising and lowering apparatus, and is more particularly applicable to lifting jacks of the class known as high speed screw jacks. The invention is further particularly applicable to that type of high speed screw jack known as the "self run-down jacks", in which the angle of the thread of the main lifting screw is sufficiently great to permit the load to force the jack down after it has been raised.

My invention is designed to provide a brake mechanism for a jack of this character by means of which both the speed and the extent of the lowering may be perfectly controlled without jarring or injury to the jack, its load, or its support, under maximum loads.

I accomplish this object by the provision of an auxiliary train of gears which is idle during the raising movement of the jack and which is arranged to be brought into action during the lowering movement; and also by the provision and connection with the auxiliary gears of a load operated automatic brake device. I also preferably provide in connection therewith a manually operated brake device.

My invention will be best understood by reference to the accompanying drawing, in which I have shown the preferred embodiment thereof and which will now be described, it being premised, however, that various changes can be made in the details of construction and arrangement of the several parts, without departing from the spirit

and scope of my invention, as defined in the appended claims.

In the drawings, the numeral 2 designates a suitable base supporting the standard 3, and 4 designates the housing of the jack provided with a sleeve portion 5, which has a sliding fit with the standard 3. 6 is the top or load supporting plate carried by the housing 4, and 7 is the main lifting screw. This screw may be actuated by any suitable or usual mechanism to raise the load. In the drawing I have indicated a beveled pinion 8 carried by a shaft 9; which may be actuated in any usual or suitable manner, the pinion meshing with the beveled gear wheel 10 rigidly fixed to the upper portion of the screw 7.

11 designates a spur gear wheel which is also fixed to the upper portion of the screw 7 above the gear wheel 10 and which meshes with the spur pinion 12 on a vertical shaft 13. This shaft 13 has a single acting-clutch 14 by which it is connected to a beveled gear wheel 15 meshing with another beveled gear wheel 16 which drives a train of multiplying gears 17. The last wheel 17^a of this train is a worm wheel, and has its teeth in mesh with a worm 18 on a transverse brake shaft 19 journaled in the housing 4.

20 is a brake disk which is slidably mounted on the shaft 19 for movement toward and away from the fixed abutment 21 (which may be formed as a part of the housing 4). This brake disk and the adjacent face of the abutment 21 are provided with suitable coöperating friction surfaces. Connected to the sleeve or hub portion 22 of the brake disk are jointed links 23 which carry the governor balls 24, the links being connected at their opposite ends to the collar 25 fixed to the shaft 19.

26 is a brake wheel which is also fixed to the shaft 19 and which is engaged by pivoted jaws 27 which are pressed against the wheel 26 by the action of a spring 28. These jaws may be separated to release their braking action by any suitable manually actuated device, such as the crank shaft 29 carrying the spreading cam 30 between said jaws.

When the jack is being raised, the spur gears 11 and 12 are revolved, but the action of the clutch 14 is such as to leave the beveled gear and the train of multiplying

gearing idle. The brake jaws 27 are pressing against the brake wheel 26, but as the clutch 14 is not operatively engaged, this braking action does not retard the raising 5 of the jack. As soon, however, as the raising effort is released, the reverse action of the main screw 7 and of the gears 10, 11 and 12 causes the clutch 14 to become operatively engaged, thereby tending to revolve 10 the auxiliary gears and the shaft 19. The brake jaws 27 are now fully operative and hold the load by preventing reverse movement of the screw 7. When self-lowering is required, the crank 29 is operated in a 15 direction to release the brake jaws 27. The shaft now commences to revolve and as the speed increases the governor balls 24 fly outwardly, thereby bringing the friction disk 20 into braking engagement with the 20 abutment 21. In this manner, the speed of self-lowering may be automatically controlled so as not to become excessive, and the load can be stopped at any desired point at any time by again turning the crank 29 to 25 permit the brake jaws 27 to again engage the brake wheel 26.

The advantages of my invention will be readily understood since it provides a self-lowering high speed screw jack which can 30 be either held against lowering movement or in which the lowering movement is automatically controlled so as not to become excessive. The auxiliary train of gears, together with the braking mechanism are 35 entirely idle during the raising movements of the jack and thereby do not materially increase the work required to raise the load, the only additional parts which move during the raising action being the spur gears 40 11 and 12.

I do not desire to limit myself to the particular form of automatic and manual brake devices which I have herein shown and described, since it will be obvious that there 45 are many devices of this character known in the arts which may be substituted for the particular forms thereof which I have herein shown and described. It will also be understood that the train of auxiliary gearing may be arranged otherwise than as shown herein and that various other changes may be made in the details of construction and arrangement of the parts within the spirit and scope of the appended 50 claims.

My invention may also be applied to other forms of load lifting apparatus.

I claim:

1. A load lifting apparatus having a 60 main lifting screw with means for actuating the same, a train of auxiliary gearing, a single acting clutch connection between the screw and the auxiliary gearing and arranged to operate the auxiliary gearing 65 only when the screw is turning in a load-

lowering direction, and a brake shaft driven by said gearing, together with an automatic speed controlled braking device operated by said shaft and auxiliary gearing; substantially as described. 70

2. A load lifting apparatus having a main lifting screw with means for actuating the same, a train of auxiliary gearing, a single acting clutch connection between the screw and the auxiliary gearing and arranged to operate the auxiliary gearing only when the screw is turning in a load-lowering direction, a brake shaft driven by said gearing, a braking member carried by said shaft, cooperating braking means normally engaging said member, and means for manually releasing the cooperating braking means; substantially as described. 75

3. A load lifting apparatus having a main lifting screw with means for actuating the same, a train of auxiliary gearing, a single acting clutch connection between the screw and the auxiliary gearing and arranged to operate the auxiliary gearing only when the screw is turning in a load-lowering direction, a brake shaft driven by said gearing, and an automatic speed controlled braking device operated by said shaft and auxiliary gearing, said shaft also having a manually controlled braking device; substantially as 80 described. 90

4. In a quick action self-lowering jack, the combination with a main screw, of an auxiliary train of gearing, a driving connection between the main screw and the train of gearing, said connection including a single acting clutch which is arranged to actuate said gearing only when the screw is turning in a load-lowering direction, a brake shaft having a worm gear connection 100 with said auxiliary train, and an automatic speed controlled brake device actuated by said shaft; substantially as described. 105

5. In a quick action self-lowering jack, the combination with a main screw, of an auxiliary train of gearing, a driving connection between the main screw and the train of gearing, said connection including a single acting clutch which is arranged to actuate said gearing only when the screw is turning in a load-lowering direction, a brake shaft having a worm gear connection with said auxiliary train, and an automatic speed controlled brake device actuated by said shaft, said shaft also having a manually controlled brake device; substantially as 110 described. 115

6. In a quick action self-lowering jack, the combination with a main load-lifting screw, of a train of auxiliary gearing having driving connection with said screw, said driving connection including a single acting clutch, and an automatic brake device actuated by said train of gearing; substantially as described. 125 120

7. In a quick action self-lowering jack, the combination with a main load-lifting screw, of a train of auxiliary gearing having driving connection with said screw, said driving connection including a single acting clutch, and an automatic brake device actuated by said train of gearing, together

with a hand controlled brake device also arranged to act upon the screw through said gearing; substantially as described. 10

In testimony whereof I have hereunto set my hand.

ISAIAH E. HINDMAN.
